UNITED STATES PATENT OFFICE.

MARGARET E. BARCLAY GEORGE, OF INDIANAPOLIS, INDIANA.

GIFT-PRESENTING CASING.

Application filed February 9, 1927. Serial No. 167,037.

This invention relates to a casing in which gifts may be carried and presented, especially by mail, the invention having reference more particularly to a casing having an ornamental figure on its front and perforated or cut away in parts to permit visibility of the article carried thereby.

An object of the invention is to provide an improved casing that shall be so constructed as to be adapted to be readily clasped so as to hold a gift article, such as a handkerchief, a necktie, a glove or stockings, as a convenient and artistic vehicle whereby the gift article may be presented in a pleasing manner or sent through the mails to a friend.

Another object is to provide an improved casing which shall be both useful and ornamental and which shall be adapted to permit the use of gift articles as portions of front ornamentation, so that many casings having one and the same ornament pattern on its front may be rendered more attractive to recipients by presenting gifts of different color in the casings.

A further object is to provide a gift-presenting casing which shall be adapted to be made principally of paper or thin card board stock and shall be simple and reliable and also have ornamental clasps, and which shall be durable and economical in use.

With the above-mentioned and other objects in view, the invention consists in a novel casing including a novel clasp for fastening parts of the casing together, the invention consisting also further in the parts and combinations and arrangements of parts as hereinafter described and claimed.

Referring to the drawings,—Figure 1 is a front view of the improved casing in which a gift article is visible through a cut away portion of the front of the casing; Fig. 2 is a plan of the casing unfolded, on a reduced scale, portions being broken away; Fig. 3 is a fragmentary detail section on the line 3—3 on Fig. 1; Fig. 4 is a fragmentary detail section on the line 4—4 on Fig. 2; and Fig. 5 is a plan of a convenient form of envelope that may be used in the casing.

Similar reference characters in the different figures of the drawings indicate corresponding elements or features of construction herein referred to in detail.

Practically the carrier is mainly composed of a sheet of material, preferably of colored or tinted paper and suitably shaped by

means of machinery and dies so as to have two cover portions 1 and 2 connected together on a folding portion or line 3, the front cover portion 2 having a keeper flap 4 connected therewith on a folding portion or line 5. The cover portion 2 has a slit 6 parallel to the line 5 and at less distance from the line than the line is from the adjacent edge of the flap 4, so that the flap 4 when folded over shall cover the slit. The flap has transverse slits 7 and 8 and the portion 2 has similar slits 7' and 8' adjacent to the slit 6 and approximately at right angles thereto, the portion 2 having also a slit 9 and a similar slit 10 likewise adjacent to the slit 6. The flap 4 has a slit 9' in alinement with a slit 9 and also a slit 10' in alinement with a slit 10.

The keeper flap 4 is folded over onto the front face of the cover part 2 so that it shall extend slightly beyond and cover the slit 6 and is suitably fastened to the front cover part, preferably by means of a ribbon threaded through the transverse slits so that the middle portion of the piece of ribbon forms a loop 11 on the front of the flap between the slits 7 and 8, and the terminal portions of the ribbon form tie ends 13 and 14 extending from the slits 9' and 10' respectively, the ribbon having tie portions 12 on the back of the part 2. The opposite part 1 has a clasp tongue 15 on its longer edge that folds on a portion or line 16 corresponding to said edge and finally is pushed through the slit 6 and held down to the face of the part 2 by the overlapping edge of the flap 4.

As an example of gift article a handkerchief 17 is illustrated and arranged on the inner side of the front cover part 2, to be held in place by the two cover parts. The front face of the cover part 2 has an artistic print or painting thereon, an example of which comprises a girl 18 wearing a suitable garment 19, such as a basque and a skirt having a bottom flounce 20, the front part 2 having an aperture corresponding in outline to the remaining portions of the skirt, the lower end of the aperture being represented by an edge 21, oppositely inclined edges 22 and 23 corresponding to the side outlines of the skirt and an upper edge 24 corresponding to the outline of the lower edge of the basque. The aperture is closed by the handkerchief which represents a real fabric skirt. The figure may be variously

ornamented, in the present case by flowers 25 carried by the girl.

Usually it is desired that the gift article be perfumed or slightly scented, for which 5 purpose a suitable envelope 26 is provided that has a flap 27, powdered perfume being placed in the envelope which is arranged on the inner side of the back part 1, with the flap of the envelope next to the part 1, 10 adhesive substance 28 being used to secure the flap and the adjacent portion of the back of the envelope to the part 1. The gift article, being in contact with the envelope is pressed slightly into the aperture 15 in the front cover part so that a realistic effect is produced in connection with the ornamentation 18.

In practical use the gift article is placed in the casing and slightly clamped therein 20 by means of the clasp devices, so that the casing and its contents may be handled as may be desired or may be inclosed in a mailing envelope and transmitted to any desired addressee. The casing may readily be 25 opened after first withdrawing the clasp tongue 15 from the slit 6. The casing may be further used for decorative or other purposes with a scrap of cloth in the place of the gift article.

30 What is claimed is:

1. A gift-presenting casing including a

front cover part and a back cover part flexibly connected together at one edge thereof, the front cover part having a keeper flap flexibly connected to its opposite edge and 35 having also a slit that is covered by the flap when the flap is folded over upon the face of the front part, the back cover part having a clasp tongue flexibly connected to its opposite edge that is insertible in said 40 slit and under the edge portion of said flap, and a device to fasten said flap to the adjacent portion of the front cover part.

2. A gift-presenting casing including an ornamental front cover part and a back 45 cover part flexibly connected together at one edge thereof, the front cover part having a keeper flap flexibly connected to its opposite edge and having also a longitudinal slit located apart from the flap, the front part and the flap having also a plurality of transverse slits in each, the back cover part having a projecting clasp tongue on its opposite edge to be inserted in the longitudinal slit, and a strip of ribbon threaded through all 50 the transverse slits and fastening the keeper flap to the adjacent portion of the front cover part.

In testimony whereof, I affix my signature on the 5th day of February, 1927.

MARGARET E. BARCLAY GEORGE.
